UNITED STATES PATENT OFFICE

2,225,807

COOLING OF INTERNAL COMBUSTION
ENGINEClifford Owen Towler, Rochester, England, as-
signor to Pobjoy Airmotors & Aircraft Limited,
Rochester, Kent, EnglandApplication January 4, 1940, Serial No. 312,426
In Great Britain January 24, 1939

3 Claims. (Cl. 123—173)

In an internal combustion engine the heat which the material of the cylinders takes up from the burning gas requires to be dissipated. This is in some cases effected by means of water or other liquid surrounding the cylinders, cylinder heads and ports, while in other instances the cooling is effected by means of air and the cylinders and cylinder heads are provided with external fins in order to expose a sufficient surface to the cooling air.

In all engines deleterious effects are produced when the temperature of the interior walls of the cylinder exceeds a certain value. Heat is transmitted from the burning gases to the cylinder barrel, cylinder head and exhaust passage in the cylinder head or barrel. Some of the heat generated by the explosions occurring in the cylinder is transmitted to the cylinder and cylinder head through the walls of the cylinder 20 and combustion chamber, and also through the walls of the exhaust port and passage.

It has been proposed to reduce the quantity of heat which is so transferred to the cylinder head or barrel by providing the exhaust passage 25 with a lining of a material of low thermal conductivity, such as asbestos, and also to provide over the lining a sleeve of heat-resisting material to assist in retaining the insulating lining in position.

It is a matter of considerable difficulty to retain the insulating lining securely in the exhaust passage of the cylinder, and according to the invention this difficulty is overcome by making the lining an integral part of the cylinder 35 head. This is done by incorporating it in the mould in which the cylinder is to be cast and casting the material of the cylinder around it.

In the case where the lining consists of asbestos, it is desirable to support it by means of 40 a sleeve of heat-resisting material, to the external surface of which the lining is applied, in which case the sleeve and lining are incorporated in the mould as a unit, but the use of such a supporting sleeve is not essential in all cases.

In an engine constructed in accordance with the invention, the quantity of heat transmitted from the exhaust gases to the material of the cylinders and therefore required to be dissipated is considerably reduced, which in liquid cooled 50 engines will have the advantage of reducing the size of radiator necessary. In aircraft engines this will decrease the drag of the aircraft, and consequently improve the performance of such aircraft.

In air cooled aircraft engines the necessary

amount of cooling air will be reduced with a consequent reduction in drag, and increased performance of the aircraft.

One form of cylinder constructed in accordance with the invention will now be described in further detail, by way of example, with reference to the accompanying drawing, in which:

Fig. 1 is a side elevation of the sleeve for supporting the insulating lining;

Fig. 2 is the corresponding end elevation; 10

Fig. 3 is a section along the line III—III in Fig. 2;

Fig. 4 is a similar section through the sleeve after coating with the insulating lining, and

Fig. 5 is a vertical section through the cylinder 15 head.

The cylinder head 10 is formed with an inlet passage 11 and an exhaust passage 12, the inlet valve 13 and exhaust valve 14 being shown as poppet valves of conventional construction. 20

The exhaust passage 12 is provided with an insulating lining 15 of asbestos supported by a sheet metal sleeve 16. As shown in Figs. 1-4 this sleeve is shaped to fit the exhaust passage, and its upper surface is formed with a recess 17 25 to accommodate the exhaust valve guide boss 18.

The sleeve 16 is first coated with the asbestos lining 15, and then incorporated in the mould in which the cylinder head is cast, thus becoming an integral part of the cylinder head. The 30 asbestos coating is prepared by mixing asbestos fibre with an adhesive to form a paste, applying the paste to the sleeve and baking in an oven until the coating has set. When perfectly dry the assembly is used as a core in the mould in 35 which the cylinder head is cast. On account of the projecting flanges of the sleeve, which become embedded in the metal of the casting, there is no risk of displacement of the sleeve or coating. 40

Although the drawing illustrates the application of the invention to a cylinder having poppet valves, it should be understood that it is also applicable to sleeve valve engines, and indeed to the exhaust ports of all types of internal 45 combustion engines.

What I claim as my invention and desire to secure by Letters Patent is:

1. In a cylinder for an internal combustion engine having an exhaust port and passage, a 50 heat insulating lining which forms a unitary part of the structure of the exhaust passage, said unitary part being integrally united with the material of the cylinder.

2. In a cylinder for an internal combustion 55

engine having an exhaust port, a heat insulating unit which forms a unitary part of the structure of, and is retained in position in the exhaust passage, said unitary part being integrally united with said cylinder, said unit consisting of a sleeve of heat-resisting material, and a layer of heat insulating material disposed on the external surface of the sleeve and constituting an insulating lining for the walls of the exhaust passage.

3. In a cylinder for an internal combustion

engine having an exhaust port, a heat insulating unit which forms a unitary part of the structure of, and is retained in position in the exhaust passage, said unitary part being integrally united with said cylinder, said unit consisting of a sleeve of heat-resisting material, and a layer of asbestos disposed on the external surface of the sleeve and constituting an insulating lining for the walls of the exhaust passage.

10
